UNITED STATES PATENT OFFICE.

HUGH F. JONES, JOHN E. LANE, AND EDWARD M. LILLIE, OF RAY, ARIZONA.

PNEUMATIC HAMMER.

1,259,409.

Specification of Letters Patent. Patented Mar. 12, 1918.

Application filed June 21, 1916. Serial No. 104,947.

To all whom it may concern:

Be it known that we, HUGH F. JONES, JOHN E. LANE, and EDWARD M. LILLIE, citizens of the United States, residing at Ray, in the county of Pinal and State of Arizona, have invented certain new and useful Improvements in Pneumatic Hammers, of which the following is a specification.

This invention relates to pneumatic hammers, and aims primarily to provide improvements in means for automatically rendering the hammer inactive or inoperative when the latter is released or disengaged from the work.

15 A further object of the invention is to provide in a hammer employing a reciprocating or movable mechanism for directing and timing the motive fluid in the piston chamber ends, improved means for utilizing 20 the motive fluid to force the controlling mechanism to the limit of its stroke in one direction, whereby the motive fluid will be precluded entrance to one end of the piston chamber, and means for exhausting the fluid 25 pressure simultaneously at the opposite piston chamber end.

With these objects in view, together with others which will appear as the description proceeds, the invention resides in the novel 30 formation, combination and arrangement of parts, all as will be described more fully hereinafter, illustrated in the drawings, and particularly pointed out in the claims.

The invention will be best understood by 35 reference to the accompanying drawings, wherein:—

Figure 1 is a longitudinal sectional view taken through a pneumatic hammer of that 40 type with which the invention is adapted more particularly for use;

Fig. 2 is a view similar to Fig. 1, the section being taken on a slightly changed plane, and illustrating the position assumed by the parts when the tool is at work;

45 Fig. 3 is a view similar to Fig. 2 and illustrating the position assumed by the parts of the control mechanism when the latter have been moved to render the tool inoperative;

50 Fig. 4 is a sectional view taken upon line 4—4 of Fig. 3;

Fig. 5 is a fragmentary sectional view similar to Fig. 4, with the parts in the position they would occupy when the hammer 55 is working; and

Fig. 6 is a slightly enlarged transverse

sectional view taken upon line 6—6 of Fig. 3.

The invention is adapted particularly for use in connection with pneumatic hammers 60 of that type wherein a sliding or reciprocating valve is employed to control the flow of motive fluid to the opposite ends of the piston chamber, to properly operate the piston. In the present illustration, there is 65 shown a familiar type of pneumatic hammer of this character for the purpose of more clearly describing the parts and operations of the improved controlling device, but it is to be understood that the invention 70 is not restricted to use exclusively in connection with the specifically constructed type of hammer, as it may with equal facility, be used with hammers of other makes 75 or types employing the reciprocating control valve.

Referring now more particularly to the drawing, the hammer cylinder is indicated at 10. This cylinder is provided at one end with a grasping handle 11, within which is 80 arranged a suitable valve operated by a thumb lever or trigger 12 for controlling the flow of motive fluid to the cylinder. The forward or working end of the cylinder is provided with a snap or tool 13, 85 adapted when the tool is in operation, to head rivets.

The slide or reciprocating valve for controlling the flow of motive fluid to the piston chamber to operate the piston 14 is indicated 90 at 15. When the valve is in the position shown in Fig. 1, fluid pressure is admitted to the rear end of the piston through the annular intake passage 16, the pressure thus acting to drive the piston forwardly, while 95 when moved to the limit of its rearward travel, the channel 16 is closed, and motive fluid is admitted through the passage 17, port 18, groove 19, and passages 20 to the forward end of the cylinder to drive the piston 14 100 rearwardly, as will be readily understood by referring to the drawings. Hammers of this type are provided with a port 21, communicating at one end with the piston chamber at substantially the medial point of the 105 latter, and at its opposite end with a rearwardly extending passage 22 communicating at its rearward extremity with a chamber 23 adjacent the slide valve and within which a shoulder 24 on the slide valve reciprocates. 110 As the piston 14 moves forwardly under the impulse of pressure admitted to the rear end

of the piston chamber, as shown in Fig. 1, the rear end of the said piston when nearing the limit of its forward or driving movement, will uncover the port 21, whereupon 5 the pressure passes into the passage 22, and thence to the chamber 23, and forces the slide valve 15 rearwardly. This movement of the valve admits motive fluid to the forward end of the hammer, whereupon the piston is 10 forced rearwardly. The means for further governing the movements of the piston or for exhausting the dead fluid, forming no part of the present invention, will not be further detailed.

15 In the present instance, the passage 22 is extended forwardly beyond the point of communication with the port 21, the said passage extension communicating with the forward end of the hammer. Arranged for 20 sliding movement within this passage extension is a plunger valve or stem 25, the forward extremity of which is held in contact with the rear face of the shoulder 26 formed upon the snap or tool by an expansion spring 27, the latter being arranged 25 within an enlarged portion of the forward part of the said passage. If desired, the forward extremity of the valve stem 25 may be headed as shown at 28 to form a suitable abut- 30 ment for the spring 27. The rear end of the stem 25 is provided with a central channel 29 having spaced right angularly disposed ports 30 and 31. The port 30 is so positioned as to communicate with the port 21 when the 35 valve is moved to the limit of its rearward travel, while, when moved forwardly, the said port is disaligned from the passage or port 21, thereby preventing motive fluid entering the passage 22. When in forward 40 position, the angularly disposed port 31 registers with a duct 32 arranged in the cylinder and in direct communication with a passage 33 leading from the main fluid passage in the handle portion of the hammer. 45 When in this latter position, fluid passes through the passage 33, duct 32, opening or port 31, channel 29, passage 22 and into the chamber 23, forcing the valve 15 rearwardly to preclude the entrance of motive fluid to 50 the rear end of the piston chamber. When in this position, the motive fluid is free to pass into the piston chamber through the passages 20 to the forward end of the tool.

To relieve the pressure which accumulates 55 at the forward end of the piston chamber when the valve 25 is moved forwardly, an exhaust port 35 is provided. This port extends laterally through the cylinder wall to permit of the escape of fluid to the atmosphere. This port is also open or closed accord- 60 ingly as the snap or tool 13 is moved. A port closing stem 36 is arranged for sliding movement in a passage or bore 37 extending inwardly from the forward end of 65 the cylinder, the said bore intercepting the

passage or exhaust port 35. The outer extremity of the stem 36 is headed as at 38, and is normally held in engagement with the shoulder 26 on the snap 13, by a spring 39. The stem 36 is of such length as to move 70 entirely free of the port 35 when the snap is moved forwardly, but closes or obstructs the exhaust port 35 when the snap 13 is forced inwardly. The stems 25 and 36 are limited in their inward and outward movement by 75 screws 40.

In operation, the hammer is operated by pressing the snap or tool thereon, against the work and depressing the trigger or thumb lever 12. The piston 14 is driven 80 backward and forward within the hammer cylinder to deliver to the snap or tool the proper blows. Should the hammer be removed from the work without severing the supply of motive fluid through the valve 85 in the handle 11, the snap 13 will, by reason of the springs 27 and 39 be forced forwardly, the valve stem 25 moving to such position as to establish communication through the passage 33 to the passage 22, 90 thence to the passage at the innermost end of the cylinder to force the valve 15 rearwardly. This at once cuts off the fluid supply at the rear end of the cylinder, but the fluid passes to the forward end through 95 the passages 20, however, immediately upon forward movement of the snap 13, the stem 36 is forced forwardly by the spring 39, opening the exhaust passage 35 to permit of the pressure at the forward end of the 100 hammer cylinder escaping to the atmosphere. Further operation of the hammer requires pressing of the snap or tool against the work to force the stems 25 and 36 rearwardly to properly actuate the valve on the 105 stem 25, and to close the exhaust port 35.

From this construction, it is apparent that we have provided a simple, positive and thoroughly efficient means for attaining the desired ends. A tool equipped with a device of this character operates to prevent blowing-out of the snap or tool upon failure of the control or throttle valve to work, whereby injury to persons in close proximity to the hammer is obviated, as well as break- 110 age or derangement of the hammer.

While the above is a description of the preferred embodiment of the invention, it is apparent that various changes in the minor details of construction and arrangement of parts may be resorted to without departing from the spirit of the invention or exceeding the scope of the claims.

What is claimed is:—

1. In a pneumatic hammer, the combination with a reciprocating valve and a sliding snap, the said hammer being provided with a passage through which the fluid is adapted to pass to reverse the reciprocating valve, of a valve in said passage adapt- 125

ed when moved in one direction to close the same and to admit fluid thereto, the said valve being operated by said snap, substantially as described.

- 5 2. In a pneumatic hammer, the combination with a reciprocating valve and a sliding snap, of a control valve in said hammer adapted when moved in one direction to admit motive fluid to said reciprocating valve
10 to force the same to the limit of travel in one direction, an exhaust valve for said hammer, and said control and exhaust valves being operated by said sliding snap, substantially as described.
- 15 3. In a pneumatic hammer having the usual longitudinally movable snap, the combination with the piston valve and the main air passage, the said hammer having a duct connecting at one end with one end of said
20 piston valve, the said main air passage, and said duct being in communication with each other, a stem moving longitudinally in said passage and extending over said communication, the said stem being hollow a short
25 distance inwardly from one end, the said hollow portion of said stem having a port adapted to register with said communication, the movements of said stem being con-

trolled by the movement of said snap, and the said port being in register with said communication when said snap is at the limit of its inward movement, substantially as described.

4. In a pneumatic hammer having the usual longitudinally movable snap, the said hammer having an exhaust port at its outer end establishing communication between the interior of said hammer and the atmosphere, the said outer end of said hammer having a longitudinal passage intersecting said exhaust port, a stem slidably arranged in said passage, a spring for holding said stem engaged with said snap, and the rear end of said stem being extended across said port to close the same only when the snap has moved to its outward limit, substantially as described.

In testimony whereof we affix our signatures in presence of two witnesses.

HUGH F. JONES.
